UNITED STATES PATENT OFFICE

DAVID GOULD, OF NEW BRITAIN, CONNECTICUT, ASSIGNOR TO THE STANLEY WORKS, OF NEW BRITAIN, CONNECTICUT, A CORPORATION OF CONNECTICUT

DOOR LATCH

Application filed March 15, 1930. Serial No. 436,057.

The present invention relates to door latches, and has for an object to provide a latch which is very simple in construction and arrangement; which may be easily applied to doors of various thicknesses, and which may be conveniently operated, in like manner, from either side of the door.

The invention embodies a novel split construction of the latch spindle and cylinder therefor adapted to extend more or less through the door and hold the spindle assembled and transmit the turning movement from one side to the other of the door, and to provide a novel thumb piece and spindle construction for interconnecting the same and admitting various adjustments to turn the spindle in the desired direction.

Other objects will be in part obvious and in part pointed out more in detail herein-after.

In the accompanying drawings, wherein is shown, more or less diagrammatically, one of the many embodiments which the present invention may take:

Figure 1 is a fragmentary outer side elevation of a door and frame therefor showing a latch constructed according to the present invention applied thereto.

Figure 2 is a vertical section taken through the same substantially on the line 2-2 of Figure 1.

Figure 3 is a horizontal section taken through the structure of Figure 1 substantially on the line 3-3 thereof.

Figure 4 is a fragmentary sectional view of the latch device, with the door and frame shown in dotted lines.

Figure 5 is a perspective view of some of the parts in separated and relative positions.

Figure 6 is a similar view with the parts adjusted in reverse position for application to the opposite edge of a door as compared with the showing in Figure 5.

Figure 7 is a detail perspective view of the thumb piece employed.

Figure 8 is a similar view of the latch guard, and

Figure 9 is a like view of a keeper.

Referring to the drawings, 15 designates a

door of any suitable construction and which is mounted in a wall or frame 16, and as shown in Figure 1, may swing outwardly or forwardly from the frame 16. The door and frame may, of course, be of any construction and the latch of this invention admits of various adjustments and mountings to accommodate doors 15 which may swing and be hinged otherwise than is shown in Figure 1.

The device comprises a latch bar 17 provided at its inner end with a round reduced head 18 which may form the inner end of the latch bar 17 and be formed therewith. Adjacent the head 18 is a spindle part 19 fixed to turn with the bar and which in cross section is semi-circular with a flat side 20 innermost and lying in the plane of the axis of the spindle. A second spindle part 21 of like semi-circular construction has a flat side 22 adapted to engage in face engagement with the flat side or face 20 so that the parts 19 and 21 when brought together provide a complete round spindle, and the parts 19 and 21 may be adjusted one upon the other in an axial direction to accommodate the spindle to doors 15 of different thicknesses and so that the spindle may project from the opposite sides of the door.

A sleeve or tube 23 receives the spindle parts 19 and 21 therein and holds the parts together in spindle form and provides a bearing in which the spindle may turn for swinging the latch bar 17. The spindle part 21 is provided upon its outer end with a head 24 which corresponds in size to the head 18 of the latch bar 17 and which is so fixed upon the spindle part 21 as to extend in the same direction as that of the head 18. The heads 18 and 24 are provided at their inner ends 25 with narrow neck portions which impart a general circular contour to the heads 18 and 24.

Handles 26 and 27 are provided, one for each side of the door 15, and these handles are substantially of the same construction. The handle 26 may be made from sheet metal with an outwardly bowed intermediate portion of suitable configuration for grasping in the hand to push and pull the door 15 into

open and closed positions. The lower end of the handle 26 is provided with an attaching flange 28 which may be turned inwardly at its margin so as to set firmly against the side 5 of the door 15 and which is suitably apertured for receiving screws 29 or the like fastening device for holding the lower end of the handle to the door.

The upper end of the handle 26 is provided 10 with a flat enlargement with an inturned marginal flange providing a casing 30 which has a depth sufficient to receive the adjacent circular head 18, or 24, and which is provided at one side and near its upper end with 15 a marginal slot 31 through which the latch bar 17 may project. The casing part 30 of the handle 26 is provided in its wall and intermediate its lateral edges with a vertically extending slot 32, the lower end or base of 20 which opens into a notch 33 formed through the wall of the casing 30. A thumb piece 34, shown in detail in Figure 7, is mounted upon each handle and has an outwardly extending finger engaging lip preferably transversely curved to fit the thumb and hold it 25 from slipping from the thumb piece. The outwardly extending lip of the thumb piece projects outwardly through the slot 32 and is located closely adjacent the upper bowed 30 part of the handle 26. The inner end of the thumb piece 34 extends upwardly within the casing 30 and is provided in one side with a socket opening 35 adapted to receive the adjacent head 18, or 24, and is of circular contour to permit of the free turning of the head 35 in the socket 35 when the thumb piece is slid vertically in the casing 30.

The inner or socket portion of the thumb piece may move up and down within the 40 limits of the slot 32 for swinging the adjacent head 18 or 24 with the spindle and the latch bar 17. The weight of the latch bar 17 normally urges the spindle in a direction to lower the latch and thus maintain the 45 thumb pieces 34 in normally raised position. The socket opening 35 of each thumb piece opens through the edge of the latter but is contracted at such edge to a degree sufficient to hold the head in the socket and the neck 50 25 of the head is reduced to a still greater extent to permit of the turning of the head in the socket and the consequent swinging of the head. There is sufficient loose play in the parts to prevent binding between the vertically moving thumb piece 34 and the pivoted 55 or swinging head 18. It will thus be seen that the upper ends of the handles constitute guide members for the thumb pieces.

For economy and simplicity in manufacture and assemblage of the parts, the socket portion of the thumb piece is constructed of a width which is slightly less than the combined lengths of the slot 32 and the notch 33 in the wall of the casing 30 so that the 60 65 thumb piece may be turned at right angles

to its final position and inserted at its socket portion through the outer wall of the casing 30 and be then swung into position with the socket portion against the inner side of the casing wall. The thumb piece 34 is also provided in opposite sides and at the inner end of its outstanding lip with notches or recesses 36 for reducing the width of the inner end of the lip to an extent sufficient to permit of the upward sliding movement of the thumb piece 34 out of the notch 33 and of the axially turning of the thumb piece 34 into upright position for use. The recesses 36 are adapted to receive the opposite edge portions of the slot 32 therein for holding the thumb piece 34 and guiding it in its vertical movements.

The opposite handle 27 is of identical construction with the handle 26 with the exception that the marginal slot in the casing 30, indicated at 37, is disposed in a side opposite to that in which the slot 31 is formed. It will also be noted that a reversely bent or constructed thumb piece 34 is employed and wherein the socket opening 35 extends through the opposite edge of the thumb piece 34 when used with the lever 27. While these slots and sockets are disposed in opposite directions, the structural features of the parts are identical. The upper end of the handle may be secured to the door by screws 38 or the like which pass through openings 39 formed through the outer wall of the casing 30 at opposite sides of the slot 32.

In order to apply or mount the latch upon a door 15 it is only necessary to form a circular bore or opening through the door to receive the tube or sleeve 23. When the sleeve is in place it is only necessary to insert the spindle part 19 into the one end of the sleeve 23 with the latch bar 17 extending in the right direction, and to insert the other spindle part 21 into the opposite end of the sleeve 23 and with the flat faces 20 and 22 of the spindle parts in engagement with each other. The tube or sleeve 23 holds the latch parts together so as to transmit turning pressure between the parts and thus insure that the spindle turns as a unit. The handles 26 and 27 with their thumb pieces 34 are applied to the opposite sides of the door with their marginal slots 31 and 37 facing toward the free edge of the door. In applying the handles, the housings 30 are so disposed over the heads 18 and 24 as to register the heads with the sockets 35 of the thumb pieces and thus the latch 17 projects outwardly through the slot 31. When the latch is to be applied to a door which opens from the left side as compared with the present illustrations, it is only necessary to reverse the positions of the handles 26 and 27 upon the opposite sides of the door. The weight of the latch bar 17 is sufficient to normally hold the heads 18 and 24 in raised position and to thus maintain both of the thumb pieces elevated so that the depression 120 125 130

of either one of the thumb pieces turns the spindle and swings the latch bar 17 into raised position. The door 15 may be provided at its free edge with a guard plate 40 which is mortised or countersunk in the front outer edge portion of the door and is suitably slotted to receive and confine the outer end of the latch 17. The door frame or wall 16 is provided with a keeper plate 41 which is mortised or countersunk in the edge of the frame and in position to receive the lower edge portion of the latch bar 17 when lowered to secure the door from swinging open.

It is obvious that various changes and modifications may be made in the details of construction and design of the above specifically described embodiment of this invention without departing from the spirit thereof, such changes and modifications being restricted only by the scope of the following claims.

I claim as my invention:

1. A door latch comprising a spindle adapted to extend through a door, a latch bar carried by said spindle, a pair of guide members attached to opposite sides of the door, a thumb piece mounted on each guide member for vertical movement thereon, and means for connecting the thumb pieces to the opposite ends of the spindle for turning the same upon movement of either thumb piece.

2. A door latch comprising a spindle adapted to be rotatably mounted in and to extend through a door and having a radially extending head on each end, a latch bar mounted on one end of said spindle, guide members for attachment to the opposite sides of the door, and a thumb piece slidably mounted on each guide member and having a socket therein for rotatably receiving the adjacent spindle head.

3. A door latch comprising a spindle adapted to be rotatably mounted in and to extend through a door and having a circular head on each end, a latch bar mounted on one end of said spindle, a pair of handles on opposite sides of the door and having casing portions for enclosing the adjacent spindle heads, and a thumb piece carried by each guide member and projecting outwardly therefrom, each thumb piece having vertical sliding movement in the guide member and having a socket opening to receive the adjacent spindle head for turning the spindle upon depression of either thumb piece.

4. A door latch comprising a latch bar, an extensible spindle to one end of which said latch bar is secured to turn therewith, and movable thumb pieces mounted on opposite sides of a door independently of the spindle and connected to the opposite ends of the spindle for turning the same and operating the latch from either side of the door.

5. A door latch comprising an extensible

spindle, a latch bar carried by said spindle, a pair of guide members for attachment to opposite sides of the door, a thumb piece mounted on each guide member for substantially vertical movement thereon, and means for connecting the thumb pieces to the opposite ends of the spindle for turning the same upon the movement of either thumb piece.

6. A door latch comprising a pair of spindle sections each having a radially extending head on its outer end and adapted for insertion in overlapping engagement through a bore in the door, a latch bar carried by one of said spindle sections, a pair of handles for attachment to opposite sides of the door, and a movable thumb piece carried by each handle, said thumb pieces having socket openings therein for rotatably receiving said heads of the spindle to turn the latter upon movement of the thumb pieces.

7. A door latch comprising a sleeve adapted to be mounted in an opening in a door, a two-part lengthwise split spindle adapted for insertion from opposite ends through the sleeve and having a circular head on the outer end of each part, a latch bar on the outer end of one of said parts, a pair of handles for attachment to the opposite sides of the door, and a thumb piece carried by each handle and projecting outwardly therefrom, each thumb piece having vertical sliding movement in the handle and having a socket opening to receive the adjacent spindle head for turning the spindle upon depression of either thumb piece.

8. A door latch comprising a pair of overlapping and interfitting spindle sections adapted for introduction through an opening in a door from the opposite sides of the door and each section having an offset head at its outer end, a latch bar carried upon the outer end of one section, a pair of handles for attachment to opposite sides of the door and having flat casing portions for enclosing said heads, and a pair of thumb pieces slidably mounted one in each handle casing and provided with sockets therein for rotatably receiving said heads, said latch bar adapted to normally maintain the thumb pieces in raised position by the weight of the bar and said thumb pieces having outwardly projecting lips for engagement with the thumb to slide the thumb pieces downwardly and rock the spindle and raise the latch bar.

9. A door latch comprising a spindle for engagement through a door and having offset heads on its opposite ends, a latch bar mounted on one end of the spindle, a pair of handles for attachment to the opposite sides of a door and each having a casing for enclosing the adjacent head of the spindle, and a pair of thumb pieces carried by the casings, each thumb piece having a vertical portion with a socket opening therein to receive the adjacent head and having an out-turned lip

and a reduced neck portion at the inner end of the lip, each casing having a vertical slot therein and a notch at the lower end of the slot, the out-turned lip portion and the vertical portion of the thumb piece being of greater width than the slot and the vertical portion of the thumb piece being of less width than the combined lengths of the slot and the notch whereby to admit of the introduction 10 and removal of the vertical portion of the thumb piece into and from the casing.
